PATTERNING MECHANISM

John Edward Lynam, Mapperley, and Patrick Gideon McCarthy, Whitwick, England, assignors to William Cotton Limited, Loughborough, England

Application July 21, 1945, Serial No. 606,400
In Great Britain March 14, 1945

2 Claims. (Cl. 66—154)

1

This invention concerns a patterning mechanism which performs sequential operations as predetermined by the lay-out of a patterning device such for example as a chain, drum, jacquard band or the like, and is primarily but not exclusively concerned with patterning mechanism in or for knitting machines.

The patterning mechanism according to this invention comprises a patterning device, means responsive to the dictates thereof, and fluid-pressure means for transmitting said dictates. The invention further includes patterning mechanism comprising a member movable by fluid pressure, a patterning device, and valve means responsive to the dictates of the patterning device for controlling the application of fluid pressure to the said member.

The patterning mechanism is preferably hydraulic, although it may be pneumatic.

These and other features of the invention set out in the appended claims are incorporated in the mechanism which will now be described as an example suitable for controlling operations in a knitting machine and for like purposes, with reference to the accompanying drawings in which—

Figure 1 is a sectional elevation of the mechanism, incorporating a diagram of the fluid supply connections.

Figure 2 is an end elevation of the mechanism. The mechanism comprises a power cylinder block 1 formed with at least one cylinder 2, (and preferably with a plurality of such cylinders as will be appreciated from Fig. 2) each containing an actuating member in the form of a piston 3 on a piston rod 4 which protrudes from both ends of the cylinder 2 through suitable glands 5, one end of each piston rod being connected by means 6 to the machine part (such for example as a cam truck) required to be moved in a manner predetermined by the lay-out of a patterning device 7. A port 8 or 9, communicates between the cylinder 2, at each side of a piston 3, with valve mechanism 10 which operates in response to the dictates of said device 7 to open either port, selectively, to fluid pressure and the other to exhaust so as to project or retract the end of the piston rod 4 and to move the said machine part by fluid pressure. The valve mechanism 10 consists of a valve cylinder 11, preferably in the cylinder block 1 or in a valve chest secured to it, with which the said ports 8, 9 communicate at axially spaced locations, an inlet to and at least one exhaust outlet from the valve cylinder, and a piston valve 12 slidable in the cylinder 11.

2

Conveniently, there is a central inlet 13 and an exhaust outlet 14a, 14b at either side of it, and the piston valve 12 comprises three spaced pistons 15a, 15b, 15c on a common piston rod 15 (i. e. being formed with two waisted portions defining three spaced lands) and is movable between a position in which one exhaust outlet 14a or 14b is covered by an end piston or land 15a or 15c, the inlet 13 communicates with one of the cylinder ports 8 or 9 by way of the waisted portion or space between said end piston 15a or 15c and the centre piston or land 15b, and the other cylinder port 9 or 8 communicates with the other exhaust outlet 14b or 14a by way of the other waisted portion or space between the centre piston 15b and the other end piston or land 15c or 15a, and an alternative position in which the first mentioned port 8 or 9 communicates with the first mentioned exhaust outlet 14a or 14b by way of the first space, the other exhaust outlet 14b or 14a is covered by the other end piston 15c, or 15a, and the second port 9 or 8 communicates with the inlet 13 by way of the second mentioned space. In Fig. 1 the piston valve 12 of the valve mechanism 10 of a representative cylinder 2 is shown as having just moved to the right hand one of its two alternative positions in which exhaust 14a is covered by land 15a, cylinder port 8 is open to inlet 13 and cylinder port 9 is open to exhaust 14b, so that fluid pressure has just been applied to the left hand side of power piston 3 and the latter is about to move to the right.

The rod 15 of each piston valve 12 is connected to a bell-crank-lever or other feeler 16 which is biased by a spring 17 into engagement with a cyclic patterning device 7 which is racked through its cycle to present a row of studs or other projections 18 set out thereon in the order required by the pattern that is to be produced, so that according to the presence or absence of a stud the piston valve 12 is moved to one or other of its two alternative positions. The outlets may be provided with adjustable needle valves.

There may be as many power cylinders, valve mechanisms and feelers as required, the patterning device 7 having the requisite number of rows of studs or the requisite number of separate devices 7 being provided. Such cyclic patterning devices are well known, and by way of example it has been elected to illustrate in a conventional manner one consisting of an endless flexible member such as a chain passing over a sprocket, drum, or the like 19 racked by mechanism indicated generally at 20 in Fig. 2.

Preferably all the power cylinders 2 and valve cylinders 11 are formed in one block 1, in which case there may be one inlet pipe and two exhaust pipes common to all the valve cylinders. The exhaust pipes drain into a sump 21 and the inlet pipe is supplied from the sump with hydraulic fluid under pressure by a pump 22 provided with a relief valve 23. An adjustable needle valve 24 is advantageously provided for throttling each exhaust outlet 14a, 14b. 24, Fig. 10, indicates a suitable frame member of a knitting machine on which the mechanism is mounted.

We claim:

1. Patterning mechanism, comprising a plurality of actuators of the piston-and-cylinder type movable individually by fluid pressure, valve mechanism for controlling the distribution of fluid pressure thereto and including a movable valve for each actuator, a cyclic patterning device having a pattern track for each valve member which track comprises a sequence of patterning elements set out to produce a predetermined sequence of movements of the associated valve and actuator, means for racking said device step by step through its cycle, and, for each track and the associated valve, a feeler movable by the pattern elements of said track to effect corresponding movement of said valve.

5

10

20

25

2. Patterning mechanism, comprising a cylinder-and-valve block formed with a plurality of cylinders each containing a piston, a plurality of valve chambers one for each cylinder and each containing a valve plunger and flow passages leading to and from opposite ends of the cylinders and controllable by said plungers to control the fluid flow to and from said opposite ends and to determine the piston movement therein; a cyclic patterning device having a plurality of pattern tracks one for each valve plunger, and feelers for moving the valve plungers in accordance with the dictates of the tracks.
